UNITED STATES PATENT OFFICE.

HENRY FRANKLIN COFFMAN, OF CARRVILLE, CALIFORNIA.

DIVIDERS.

1,108,706.

Specification of Letters Patent. Patented Aug. 25, 1914.

Application filed April 24, 1914. Serial No. 834,185.

To all whom it may concern:

Be it known that I, HENRY F. COFFMAN, a citizen of the United States, residing at Carrville, in the county of Trinity, State 5 of California, have invented certain new and useful Improvements in Dividers; and I do hereby declare the following to be a full, clear, and exact description of the invention, such as will enable others skilled 10 in the art to which it appertains to make and use the same.

The present invention is directed to improvements in dividers, and has for its object to so construct an instrument of this 15 character particularly designed for finding the exact center of a circle.

A further object of the invention is to provide a divider which can be easily and quickly adjusted for finding the centers of 20 circles of different diameters, and further provide a device which may be used to find the center of pipe sections.

With these and other objects in view, this invention resides in the novel features of 25 construction, formation, combination and arrangement of parts to be hereinafter more fully described, claimed and illustrated in the accompanying drawing, in which:—

Figure 1 is a side elevation of the device. 30 Fig. 2 is an edge view. Fig. 3 is a sectional view on the line 3—3 of Fig. 1. Fig. 4 is a partial central sectional view. Fig. 5 is a sectional view on line 5—5 of Fig. 1. Fig. 6 is a fragmentary perspective view 35 of one of the divider legs.

Referring to the drawing, the numeral 1 designates the head, the same being provided with grooves 2 which coact with the curved edges 3 formed in the upper ends 40 of the divider legs 4, said legs being held in the grooves by the bowed leaf spring 5, the ends of which engage the notches 6 formed in the upper ends of said legs.

The centering pin 7 is threaded in the 45 bore 8 formed in the head 1, and has its upper end provided with a knob 9 which

when rotated will raise or lower said pin. The upper end of the pin 7 is operable in the perforation 10 formed in the spring 5.

Pivotedly mounted upon the legs 4 are 50 lugs 11, said lugs being threaded for engagement by the adjusting screw 12, which is oppositely threaded so that rotation in one direction will draw the legs toward each other, and when rotated in another 55 direction the legs will be spread, each end of said screw being provided with the operating knob 13. It will be of course understood that the threads of the lugs 11 are pitched oppositely.

Fixed in spaced relation upon the central part of the screw 12 are disks 14 which span the pin 7 so that upon adjustment of the legs 4 the point of the pin 7 will be at all times positioned at an equal distance 65 from the points of the legs.

From the foregoing description it will be seen that the pin 7 can be readily elevated when not in use, and that the legs 4 can be adjusted independently of the pin. 70

What is claimed is:

A divider of the class described comprising a head, legs having their upper ends loosely engaging said head, a centering pin threaded through the head, lugs pivotally 75 mounted upon the legs, an adjusting screw engaged in said lugs, spaced disks carried by the adjusting screw and spanning the centering pin, whereby upon rotation of the adjusting screw the legs may be expanded 80 or contracted to regulate the distances between their points and the point of the centering pin, and a knob carried by the upper end of the centering pin to facilitate 85 the rotation of the pin, as and for the purpose set forth.

In testimony whereof, I affix my signature, in the presence of two witnesses.

HENRY FRANKLIN COFFMAN.
